(57) **CLAIM**

The ornamental design for a food packaging, as shown and described.

DESCRIPTION

FIG. 1 is a right-front perspective view of a food packaging showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the figures illustrate the portions of the food packaging and form no part of the claimed design. The broken lines on the bottom surface of the food packaging in FIG. 7 are included to show unclaimed perforation lines on the article.
